ROTARY PUMP OR MOTOR

Ferdinand M. Weyer, Detroit, Mich., assignor to
Marine Products Company, Detroit, Mich., a
corporation of Michigan

Application November 22, 1946, Serial No. 711,517

12 Claims. (Cl. 103—117)

1

This invention relates to fluid pressure machinery and in particular to fluid pressure pumps or motors.

One object of this invention is to provide a fluid pressure pump or motor having a rotor of resilient material, a portion of which flexes as it passes abutments arranged between the intake and outlet of the pump casing, thereby providing an effective barrier between the suction and discharge sides of the pump in a simple and efficient manner.

Another object is to provide a fluid pressure pump or motor as set forth in the preceding object wherein the end plates of the pump casing are provided with inwardly extending abutments and the rotor is provided with resilient vanes which engage these abutments and flex axially toward one another as they pass the abutments.

Another object is to provide a fluid pressure pump or motor, as set forth in the preceding object, wherein the peripheral inner wall of the pump casing is substantially cylindrical and the axis of the rotor shaft is substantially concentric therewith so that the resilient vanes constantly contact this peripheral inner wall without the necessity of radial flexing or yielding as the rotor rotates.

Another object is to provide a fluid pressure pump or motor, as set forth in the preceding objects wherein the abutments are formed on separate end plate liners so that the manufacture of the pump is simplified and its cost of production reduced.

Other objects and advantages of the invention will become apparent during the course of the following description of the accompanying drawings, wherein:

Figure 1 is a central vertical longitudinal section through a fluid pressure pump or motor according to a preferred form of the invention;

Figure 2 is a central vertical cross-section through the pump or motor shown in Figure 1, with the rotor mainly in side elevation but partially broken away to disclose its peripheral construction;

Figure 3 is an irregular generally horizontal section through the pump or motor shown in Figures 1 and 2, taken along the partially arcuate line 3—3 in Figure 2;

Figure 4 is a top plan view of the rotor removed from the pump or motor;

Figure 5 is a side elevation of an abutment plate removed from the pump or motor; and

Figure 6 is an edge elevation of the abutment plate shown in Figure 5.

Referring to the drawings in detail, Figure 1 shows a preferred form of the fluid pressure pump or motor of this invention as consisting of a housing, generally designated 10, supported upon a pedestal 11 integral therewith and having a base portion 12 at the bottom thereof for mounting the pump upon any suitable support. The housing 10 above the pedestal 11 is provided with a journal portion 13 having a bearing bore 14 (Figure 1) therethrough, and also having a

2

threaded hole 15 leading thereto. Mounted in the threaded hole 15 is the tubular shank 16 of a lubricator 17. The lubricator 17 is conventional and may consist of an oil or grease cup or a fitting for a conventional pressure lubrication device. The right-hand or outer end of the journal portion 13 terminates in an annular recess 18 threaded as at 19 to receive an annular plug or gland 20 adapted to compress an annular packing 21 in the recess 18.

The housing 10 at its opposite end is enlarged to provide the disc-like end wall 22 of an approximately cylindrical casing portion 23 having intake and outlet bosses 25 and 24 respectively with threaded intake and discharge ports 27 and 26 leading into a cylindrical rotor chamber 28. The open edge 29 of the casing portion 23 is engaged and closed by an approximately circular end plate 30 bolted or otherwise secured thereto as at 31.

20 Journaled in the bearing bore 14 is a rotor shaft 32, the latter passing through the packing 21 and the hole 33 through the center of the gland 20. Mounted on the outer end of the shaft 32 is the hub 34 of a pulley 35 having a bore 36 for receiving the shaft 32 and a set screw 37 threaded through the radial hole 38 therein for securing the pulley 35 to the shaft 32. The pulley 35 is provided with the usual groove 39 for receiving a belt (not shown) by which the device is driven, if used as a pump, or which transmits power from the shaft 32 in the event that the device is used as a motor.

25 The inner end of the shaft 32 is splined as at 40 to receive the correspondingly grooved hub 41 of a rotor or impeller generally designated 42. The hub 41 is provided with a disc-like flange 43 having circumferentially spaced holes 44 therein. The flange 43 serves to receive the resilient core 45 of the rotor 42 and is made of elastic deformable material such as rubber or synthetic rubber. The material of the core 45 extends through the holes 44 and locks the core 45 firmly to the hub 41.

30 Integral with the core 45 and extending radially outward from the hub 41 are vanes 46 likewise of elastic deformable material such as rubber or synthetic rubber. The radially-extending edges 47 of the vanes 46 are enlarged so as to be rod-like and of circular cross-section. The outer or peripheral ends 48 of the vanes 46 snugly engage the inner wall of the cylindrical chamber 28, which is co-axial with the shaft 32. The core 45 is extended axially as at 49 at its opposite end to encircle the hub 41 and to cover the latter with a tubular layer of the elastic deformable material.

35 The periphery of the core 45 is extended outwardly around the rim of the flange 43 of the hub 41 to provide a resilient annular portion 50 interconnecting the vanes 46 near their outer ends (Figure 2). Thus, the core 45 in cross-section is approximately in the shape of two truncated triangles extending in opposite directions with their bases adjacent the hub 41 (Figure 1).

Extending axially outward from the chamber 28 in the end wall 22 and end plate 30 are oppositely directed sockets 51 and 52 (Figure 1). Mounted within the chamber 28 are disc-like abutment plates 53 and 54 of circular shape and having holes 55 through the centers thereof for the passage of the shaft 32. The abutment plates 53 and 54 are of similar configuration but of right-hand and left-hand construction, having approximately sector-shaped abutment portions 56 and 57 respectively bulging axially inward toward one another (Figures 1, 5 and 6). The abutment portions 56 and 57 are struck out of the abutment plates 53 and 54, such as by appropriate discs.

The abutment plates 53 and 54 are secured within the chamber 28 (Figure 1) by being provided with axially projecting portions 58 and 59 of tubular rivet-like form integral therewith and seated in the sockets 51 and 52. In this manner, the abutment plates 53 and 54 are held securely in position and also prevented from rotating. It will be understood that the abutment portions 56 and 57 may be formed integral with the end wall 22 and end plate 30 respectively, but in actual production it is found more economical to form them upon the separate abutment plates 53 and 54.

In the operation of the device as a pump, intake and discharge conduits (not shown) are connected to the intake and discharge ports 26 and 27 and the pulley 35 is connected to a source of power, such as an engine, by a suitable belt (not shown).

As the shaft 32 is rotated by the pulley 35 in a clockwise direction (Figure 2), fluid is drawn in through the intake port 27 and expelled through the discharge port 26. As the vanes 46 pass the inwardly extending abutments 56 and 57, their enlarged edge portions 47 are pushed inwardly toward one another in an axial direction (Figure 3) causing the vanes 46 to flex arcuately. This action not only provides an effective seal between the intake and discharge ports 27 and 26, but also reduces the volume between adjacent vanes 46, expelling the fluid contained between the flexed vane and the unflexed vane (Figures 2 and 3), through the discharge port 27.

If the device is used as a motor, pressure fluid is supplied to the chamber 28 through the intake port 27. This pressure fluid acts against the vanes 46, causing rotation of the rotor 42 and shaft 32, the fluid being discharged through the discharge port 26. As the vanes 46 pass the abutment portions 56 and 57, they are flexed as described above, and a seal is established between the intake and discharge ports 27 and 26. The power thereby imparted to the shaft 32 is transmitted by a belt on the pulley 39 to any suitable source of utilization.

The device is well adapted for use as a pump for handling water, and is especially well suited for service as a bilge pump. Since the vanes 46 are flexed only in an axial direction (speaking with reference to the axis of rotation of said rotor) and retain a constantly straight shape in a radial direction, they have a long life and are dependable in operation. The use of water in connection with a rubber or rubber-like rotor 42 provides a lubricating action between the vanes 46 and the metallic parts which they engage, resulting in a reduction of friction and a smooth operation with a minimum of wear.

While a pulley has been shown for transmit-

ting power to or from the shaft 32, it will be obvious that gearing or other suitable conventional mechanism may be used for the same purpose.

While I have shown and described my invention in detail, it is to be understood that the same is to be limited only by the appended claims, for many changes may be made without departing from the spirit and scope of my invention.

What I claim is:

1. A rotary pump or motor comprising a hollow casing having circumferentially-spaced fluid intake and discharge ports therein, and having

15 a peripheral wall and axially-spaced end walls, a rotor of elastic deformable material rotatably mounted in said casing upon an axis of rotation transverse to said end walls and having radially-disposed resilient vanes engaging said walls, and 20 a radially-disposed abutment projecting axially inward from one of said end walls between said ports and engageable with the radially-extending edges of said vanes to flex said vanes in a direction approximately parallel to said axis of rotation of said rotor.

2. A rotary pump or motor comprising a hollow casing having circumferentially-spaced fluid intake and discharge ports therein, and having

30 a peripheral wall and axially-spaced end walls, a rotor of elastic deformable material rotatably mounted in said casing upon an axis of rotation transverse to said end walls and having radially-disposed resilient vanes engaging said walls, and 35 a radially-disposed abutment of approximately sector-shape projecting axially inward from one of said end walls between said ports and engageable with the radially-extending edges of said vanes to flex said vanes in a direction approximately parallel to said axis of rotation of said rotor.

3. A rotary pump or motor comprising a hollow casing having circumferentially-spaced fluid intake and discharge ports therein, and having

45 a peripheral wall and axially-spaced end walls, a rotor of elastic deformable material rotatably mounted in said casing upon an axis of rotation transverse to said end walls and having radially-disposed resilient vanes engaging said walls, and 50 a radially-disposed abutment projecting axially inward from one of said end walls between said ports and engageable with the radially-extending edges of said vanes to flex said vanes in a direction approximately parallel to said axis of rotation of said rotor; said peripheral wall having 55 an internally cylindrical configuration and said rotor being mounted upon an axis of rotation co-incident with the axis of said peripheral wall.

4. A rotary pump or motor comprising a hollow casing having circumferentially-spaced fluid intake and discharge ports therein, and having

60 a peripheral wall and axially-spaced end walls, a rotor of elastic deformable material rotatably mounted in said casing upon an axis of rotation transverse to said end walls and having radially-disposed resilient vanes engaging said walls, and 65 a radially-disposed abutment of approximately sector-shape projecting axially inward from one of said end walls between said ports and engageable with the radially-extending edges of said vanes to flex said vanes in a direction approximately parallel to said axis of rotation of said rotor, said peripheral wall having an internally 70 cylindrical configuration and said rotor being 75

mounted upon an axis of rotation co-incident with the axis of said peripheral wall.

5. A rotary pump or motor comprising a hollow casing having circumferentially-spaced fluid intake and discharge ports therein, and having a peripheral wall and axially-spaced end walls, a rotor of elastic deformable material rotatably mounted in said casing upon an axis of rotation transverse to said end walls and having radially-disposed resilient vanes engaging said walls, and a pair of radially disposed abutments projecting axially inward toward one another from said end walls between said ports and engageable with the opposite radially extending edges of said vanes to flex said opposite radially-extending edges of said vanes toward each other in a direction approximately parallel to said axis of rotation of said rotor.

6. A rotary pump or motor comprising a hollow casing having circumferentially-spaced fluid intake and discharge ports therein, and having a peripheral wall and axially-spaced end walls, a rotor of elastic deformable material rotatably mounted in said casing and having radially-disposed resilient vanes engaging said walls, and a pair of radially disposed abutments of approximately sector-shape projecting axially inward toward one another from said end walls between said ports and engageable with the opposite radially extending edges of said vanes to flex said opposite radially-extending edges of said vanes toward each other in a direction approximately parallel to said axis of rotation of said rotor.

7. A rotary pump or motor comprising a hollow casing having circumferentially-spaced fluid intake and discharge ports therein, and having a peripheral wall and axially-spaced end walls, a rotor of elastic deformable material rotatably mounted in said casing and having radially-disposed resilient vanes engaging said walls, and a radially-disposed abutment member in said casing having an abutment portion projecting axially inward from one of said end walls between said ports and engageable with the radially-extending edges of said vanes to flex said vanes in a direction approximately parallel to said axis of rotation of said rotor.

8. A rotary pump or motor comprising a hollow casing having circumferentially-spaced fluid intake and discharge ports therein, and having a peripheral wall and axially-spaced end walls, a rotor of elastic deformable material rotatably mounted in said casing and having radially-disposed resilient vanes engaging said walls, and a radially-disposed abutment member in said casing having an abutment portion of approximately sector-shape projecting axially inward from one of said end walls between said ports and engageable with the radially-extending edges of said vanes to flex said vanes in a direction approximately parallel to said axis of rotation of said rotor.

9. A rotary pump or motor comprising a hollow casing having circumferentially-spaced fluid intake and discharge ports therein and having a peripheral wall and axially-spaced end walls, a rotor of elastic deformable material rotatably mounted in said casing and having radially-disposed resilient vanes engaging said walls, and a radially-disposed abutment member in said casing having an abutment portion projecting axially inward from one of said end walls between said ports and engageable with the radially-extending edges of said vanes to flex said

vanes in a direction approximately parallel to said axis of rotation of said rotor, said peripheral wall having an internally cylindrical configuration and said rotor being mounted upon an axis of rotation co-incident with the axis of said peripheral wall.

10. A rotary pump or motor comprising a hollow casing having circumferentially-spaced fluid intake and discharge ports therein and having a peripheral wall and axially-spaced end walls, a rotor of elastic deformable material rotatably mounted in said casing upon an axis of rotation transverse to said end walls and having radially-disposed resilient vanes engaging said walls, and a pair of radially-disposed abutments projecting axially inward toward one another from said end walls between said ports and engageable with the opposite radially extending edges of said vanes to flex said opposite radially-extending edges of said vanes toward each other in a direction approximately parallel to said axis of rotation of said rotor, said peripheral wall having an internally cylindrical configuration and said rotor being mounted upon an axis of rotation co-incident with the axis of said peripheral wall.

11. A rotary pump or motor comprising a hollow casing having circumferentially-spaced fluid intake and discharge ports therein and having a peripheral wall and axially-spaced end walls, a rotor of elastic deformable material rotatably mounted in said casing upon an axis of rotation transverse to said end walls and having radially-disposed resilient vanes engaging said walls, and a pair of spaced abutment members within said casing having radially-disposed abutment portions projecting axially inward toward one another between said ports and engageable with the opposite radially extending edges of said vanes to flex said opposite radially-extending edges of said vanes toward each other in a direction approximately parallel to said axis of rotation of said rotor.

12. A rotary pump or motor, comprising a hollow casing having circumferentially-spaced fluid intake and discharge ports therein and having a peripheral wall and axially-spaced end walls, a rotor of elastic deformable material rotatably mounted in said casing upon an axis of rotation transverse to said end walls and having radially-disposed resilient vanes engaging said walls, and a pair of spaced abutment members within said casing having radially-disposed abutment portions projecting axially inward toward one another between said ports and engageable with the opposite radially extending edges of said vanes to flex said opposite radially-extending edges of said vanes toward each other in a direction approximately parallel to said axis of rotation of said rotor, said abutment portions being of approximately sector-shape.
